UNITED STATES PATENT OFFICE

119,212

DESIGN FOR A COMBINED BUCK AND COLLAR HOLDER FOR A SHOULDER AND YOKE IRONING PRESS

Charles P. Downer, Winchester, and Harry G. Cooper, Medford, Mass., assignors to The Prosperity Company, Inc., Syracuse, N. Y., a corporation of New York

Application December 28, 1938, Serial No. 82,026

Term of patent 14 years

To all whom it may concern:

Be it known that we, Charles P. Downer, a citizen of the United States of America, residing and having his post-office address at 17 Wildwood Street, Winchester, in the county of Middlesex and State of Massachusetts, and Harry G. Cooper, a citizen of the United States of America, residing and having his post-office address at 34 Grove Street, Medford, in the county of Middlesex and State of Massachusetts, have invented a new, original, and ornamental Design for a Combined Buck and Collar Holder for a Shoulder and Yoke Ironing Press, of which the following is a specification, reference being had to the accompanying drawing, forming part thereof.

Figure 1 is a top plan view of a combined buck and collar holder for a shoulder and yoke ironing press showing our new design.

Figure 2 is a front view thereof.

Figure 3 is a rear view thereof.

Figure 4 is a side view thereof.

What is claimed is:

The ornamental design for a combined buck and collar holder for a shoulder and yoke ironing press, substantially as shown.

CHARLES P. DOWNER.
HARRY G. COOPER.
